MAGNETIC DOOR SEAL

Lloyd L. Anderson and Nathan S. Waring, Grand
Rapids, and Anton W. Korb, Grandville, Mich.,
assignor to Jervis Corporation, a corporation
of Michigan

Application March 23, 1950, Serial No. 151,462

1 Claim. (Cl. 20—69)

1

This invention relates to a door seal and closure which has been designed, primarily for use in conjunction with refrigerators or the like, wherein it is desirable that an entrance door to interior space in the refrigerator be tightly closed and sealed against escape of refrigerated air from the interior of the casing or entrance of heat from outside.

With my invention, a novel, useful and practical structural device is provided for magnetically holding a refrigerator door or the like in closed position, and maintaining an effective seal entirely around the edge portions of the door, the door preferably carrying a novel structure of sealing gasket which in turn carries magnetically attractive means, while the refrigerator casing, around the entrance opening thereto, is supplied with spaced permanent magnets which, when the door approaches or comes to its closed position, magnetically attract the responsive material carried by the gasket so as to hold such gasket securely in sealing position against the casing at the faces thereof surrounding the door opening.

It is an object and purpose of the present invention to provide a novel, practical door sealing structure of the type indicated and in which, opening the door against the magnetic forces tending to hold it in closed position, is rendered more easy through a novel structure of gasket in association with the magnets which attract the gasket, in short a lesser amount of force is necessary to open the door than has been previously required. However, because of the novel combination herein illustrated, such result is obtained without detrimental effect upon the sealing functions performed.

An understanding of the invention may be had from the following description, taken in connection with the accompanying drawing, in which

Fig. 1 is a front elevation illustrating a refrigerator equipped with my invention, a portion of the door being broken away.

Fig. 2 is a fragmentary enlarged horizontal section, substantially on the plane of line 2—2 of Fig. 1, with the door in closed sealing position.

Fig. 3 is a like view showing the door slightly pulled away from the casing for the magnetic seal release.

Fig. 4 is a fragmentary vertical section substantially on the line of 4—4 of Fig. 2 and

Fig. 5 is a transverse vertical section substantially on the line 5—5 of Fig. 3.

Like reference characters refer to like parts in the different figures of the drawing, and the sectional views are taken looking in the directions

2

indicated by the arrows associated with the respective section lines.

The refrigerator casing, indicated at 1, is open at its front side which is closed by a hinged door 2 in the usual manner. Around the entrance opening to the refrigerator, a number of permanent magnets 3 are mounted, spaced from each other as best shown in Fig. 1. Each of the magnets forms a part of a unit. The magnets have a generally horseshoe type, their ends or poles being inserted through a flat base plate 4 over which is a stirrup 5 of sheet metal, welded at its ends to the base. A screw 6 through the stirrup 5 bears against the magnet 3 (Fig. 4) to bind the magnet in place against movement.

The face of the refrigerator casing at the places where the magnets are installed has openings made through the metallic covering at such face. The intermediate portions of the bases 4, offset 20 as shown in Fig. 4, enter such openings so that the outer faces of the bases 4 are flush with the outer face of the refrigerator casing at all places where the magnets are installed around the entrance opening. The base plates 4 are welded or otherwise permanently secured to the metal covering of the refrigerator casing.

At the inner side of the door, adjacent all of its edges, a sealing gasket is secured. The gasket has a base member 7, permanently secured at the inner side of the door 2 as shown in Figs. 2 and 3. The gasket, preferably of rubber or plastic compound, has two spaced apart sides 8 and 9 extending therefrom which are integrally connected by an inner face or side 10. The face 10 when in a free position, as when the door is open, lies in a plane at an acute angle to the plane of the inner side of the door, the side 9 being longer than the side 8 (Fig. 3). When the door is closed and the outer side or face 10 presses against the front face of the refrigerator around the entrance opening so as to be parallel to the base member 7, the longer side 9 is forced into an outward arc shape, as shown in Fig. 2. It is evident that the gasket is hollow, the inner space being surrounded by the base 7, sides 8 and 9 and the inner face 10.

Within such space, integral with the inner face 10 of the gasket, a continuous channel 11 of rubber is located which, with the inner face 10 of the gasket, provides a continuous, elongated chamber of a generally rectangular form within which, with our invention, magnetically attractive material is placed and retained as indicated at 12. Such material may be in a powdered form and 50 completely fill the elongated chamber provided

for it. It also may be used to thoroughly and homogeneously impregnate strips of rubber material or other carrier for the powdered material. Such powdered or finely divided material, which may be soft particles or particles of iron oxide, or other equivalent material which is attracted by magnetic attraction, may be used to impregnate a mass of the carrier material and the whole extruded in a desired cross section and, if necessary, vulcanized or otherwise treated after such extrusion.

When the door is closed the attraction of the permanent magnets 3 upon the magnet attracted material at 12 first begins to exert its force upon the material which first comes within the range of the fields of the magnets, that is the material at the inner sides of the parts at 12. Then, as the door is closed, and the gasket distorted from the form shown in Fig. 3 to that shown in Fig. 2, the full force of the magnets 3 is asserted upon such material. This will hold the door snugly closed in sealed position.

It will be noted that the magnets 3, in the succession of magnets around the entrance opening to the refrigerator, have north and south poles of adjacent magnets presented to each other so that the material at 12, influenced by the magnets, between the adjacent magnets 3 becomes in effect a series of successive magnets with poles properly positioned to obtain the greatest effect of the magnetic attraction and thus hold the door closed at a maximum efficiency of the magnets used.

The door is opened by pulling on a handle at the outer side of and located adjacent to the free vertical edge of the door. The pull first withdraws the magnet attracted material at 12 from the magnets at the outer side edges thereof requiring a less exertion than if the entire force of attraction between the magnets and the material at 12 had to be overcome. This occurs in conjunction with the magnets located at the

5 vertical sides of the door opening. At the upper and lower sides the magnets there mounted are taken care of by successively breaking their forces exerted upon the gasket, so that the door may be more readily and easily opened without the expenditure of undue force.

10 The structure described is of a simple and practical type. The number of magnets 3 to be used may be restricted to a minimum. The invention is defined in the appended claim and is to be considered comprehensive of all forms of structure coming within their scope.

We claim:

15 In a structure as described, a casing having an entrance opening at its front side said casing having walls surrounding the opening and front faces to said walls having spaced openings therein, a plate secured at the rear side of said front face at each opening therein, said plate having an opening at its intermediate portion, a magnet located at the inner side of each of the plates having spaced poles extending through the opening in its associated plate and bearing against said associated plate, a member secured to each of said plates spaced therefrom, between which and each the said plates the magnet is located, and a screw threading through each of said members bearing against its associated magnet to secure it in place.
